UNITED STATES PATENT OFFICE.

JOHN F. C. YTTRUP, OF PITTSBURGH, PENNSYLVANIA.

HAND-GRENADE.

1,272,759.

Specification of Letters Patent. Patented July 16, 1918.

Application filed February 4, 1918. Serial No. 215,246.

To all whom it may concern:

Be it known that I, JOHN F. C. YTTRUP, a subject of the King of Denmark, and a resident of Pittsburgh, in the county of Allegheny and State of Pennsylvania, have invented a new and useful Improvement in Hand-Grenades; and I do hereby declare the following to be a full, clear, and exact description thereof.

10 This invention relates to bombs or projectiles, and more particularly to grenades adapted primarily for hand throwing, and has for one of its principal objects the provision of a device of this class that may be 15 safely handled by the operator without danger of premature explosion.

Another object is the provision of a grenade that will explode at a predetermined time, and one in which the detonator will be 20 fired by the action of the device passing through the air.

Other objects, such as simplicity and cheapness in manufacture, will be more fully brought out in the specification and illustrated in the accompanying drawings, in 25 which:

Figure 1 is a sectional view through a complete grenade embodying my invention;

Fig. 2 is a sectional view at right angles 30 to Fig. 1.

Referring more particularly to the drawings, the numeral 2 designates the body portion of my grenade, which is preferably composed of tin and made pear shaped in 35 order that it may be readily grasped by the operator, and also to facilitate its travel through space. The upper or small end of the body is screw-threaded to receive a cap 3, having a centrally arranged aperture 4 40 in the end 3' of said cap. The upper or small end of the body portion 2 has an internal flange 5 formed adjacent its terminal. A tube like receptacle 6 having a flange 7 is adapted to extend within the body portion 2 and be supported by the flange 5.

The body portion 2 is adapted to be filled with any well known explosive 8 requiring a shock to set it off, and to have at its head or large end an inner head 9 of cast metal 50 or other charge. The head 9, which I prefer formed of cast metal, is crossed by separation channels 10 at intervals, such channels or lines running at right angles to each other so as to divide such inner head into 55 small squares which will separate when the device explodes.

The tube-like receptacle 6 is partially filled with a strong explosive 11, such as mercury powder, and contains a fuse strip 12 which has slow burning qualities and 60 which will burn a predetermined time, as for example 8th inch per second.

An inverted cup-shaped member 13 is mounted above the cap 3 and contains a coil spring 14. An ignition wire 15 is secured 65 to the cup 13 and extends through the aperture 4 and within the receptacle 6, and has an inflammable head 16.

The spring 14 is of such length that it must be compressed under the cup 13 in order to allow the wire 15 which is secured to such cup to extend within the receptacle 4, and when compressed it is held in position by the locking arms 17 which are secured to the sides of cap 3 and bent over the 75 cup 13.

The arms 17 are held in position over the cup member 13 by the cord 18 which is wrapped around the free ends of such arms and has its one end trained downwardly 80 under the inclosing tube or neck 19, which is removably secured to the small end of the body portion 2. The cord 18 is then trained upwardly and has its end secured in a stopper member or cork 20 adapted to be 85 secured in the tube or neck 19.

The operation of the device is as follows:

The device being assembled and filled with the suitable explosives, the operator will grasp it so that the large end will leave 90 his hand first; he will remove the cork or stopper 20 which is composed of light material, such as cork or wood; he will then remove the neck 19 and grasp the stopper 20 under the thumb of the throwing hand. 95

The operator will then throw the device into the air in a forward direction, and the pear shape of the body portion will cause such body to travel with its large or head end inclined toward the ground. Such position will aid in scattering the charge or inner head 9.

The stopper or cork 20, being light, will travel to the rear of the device at the length of the string or cord 18. The peculiar shape 105 of the body portion 2 and the manner in which it is gripped by the operator will cause the device to have a whirling action when thrown into the air. The circling or whirling action of the body 2 will cause the cord 18 to unwind from the locking arms 17, thus releasing the same and permitting 110

spring 14 to force the cup member 13 upward, thereby causing the head 16 on the wire 15 to ignite. This is due to the friction caused by the head 16 in passing 5 through the aperture 4 in cap 3 striking the sides of said aperture. When the head 16 ignites it will start the fuse 12 and thus set off the charge 11 which acts as a detonator to set off the main explosive charge 8.

10 It will thus be seen that it is impossible for a grenade constructed according to my invention to prematurely explode thus injuring the operator and companions.

It will be understood that the cord 18 may 15 be wrapped around the arms 17 any number of times desired, thus increasing or decreasing the length of time required for the device to explode after being thrown into the air.

20 Although I have shown and described my invention in combination with a specific form of grenade, it will be understood that various changes may be made in design and construction by those skilled in the art, 25 without departing from the spirit of my invention as defined in the appended claims.

What I claim is:

1. The combination with a projectile comprising a body portion of relatively thin 30 metal to contain explosives, a detonator, and ignition means, of an inner head of relatively thick cast metal arranged in the head of said projectile, said cast head having dividing grooves on its inner surface in 35 checker formation to facilitate its breaking apart when the device is exploded.

2. A projectile comprising a body portion to contain explosive, a detonating tube within said body portion, an automatic ignition means, said means comprising a spring accelerated stem extending within said tube, means for locking said stem in inoperative position, said means comprising locking arms bent over said stem to depress the same, 45 and means for releasing said arms.

3. In a hand grenade, a detonator comprising a tubular receptacle partially filled with an explosive, a fuse within said receptacle, an ignition stem extending into said 50 receptacle to ignite said fuse, a spring member compressed under a cup member, a pair of locking arms adapted to be bent over said cup to hold said spring in its compressed position, and a flexible cord member wound 55 around the free ends of said arms to hold them in position, said cup being secured to

said ignition stem, and said stem being ignited when said spring and cup are released.

4. A hand grenade comprising a pear-shaped body portion composed of relatively thin metal to contain an explosive, a head of relatively thick cast metal having dividing grooves on its inner surface at intervals and extending at right angles to each other dividing said head into small squares to facilitate its breaking apart when the device is exploded, and a detonator for discharging said explosive. 60 65

5. A hand grenade comprising a pear-shaped body portion composed of thin metal to contain an explosive, a detonator for said explosive, said detonator comprising a tubular receptacle partially filled with an explosive, a fuse within said receptacle, an ignition stem extending into said receptacle 70 to ignite said fuse, a spring member compressed under a cap, a pair of locking arms bent over said cup members to hold said spring in its compressed position, and a flexible cord member adapted to be wound 75 around the free ends of said arms to hold them in position, said cup being secured to said ignition stem, and said stem being ignited when said spring and cup are released. 80 85

6. A hand grenade comprising a pear-shaped body portion composed of relatively thin metal to contain an explosive, a head of relatively thick cast metal having dividing lines therein to facilitate it breaking apart 90 when the device is exploded, a detonator for discharging said explosive, said detonator comprising a tubular receptacle partially filled with an explosive, a fuse within said receptacle, an ignition stem extending into said receptacle to ignite said fuse, a spring member compressed under a cup member, a pair of locking arms bent over said cup member to hold said spring in its compressed position, and a flexible cord member wound around the free ends of said arms 95 100 to hold them in position, said cup being secured to said ignition stem, and said stem being ignited when said spring and cap are released. 105

In testimony whereof, I, the said JOHN F. C. YTTRUP, have hereunto set my hand.

JOHN F. C. YTTRUP.
